ELEVATOR CLOSURE OPERATING
MECHANISMWestropp Armstrong, Philadelphia, Pa., assignor
to Armstrong Riding Car Operator Corp., Chi-
cago, Ill., a corporation of Illinois

Application June 28, 1949, Serial No. 101,734

17 Claims. (Cl. 187—58)

1 This invention relates generally to a mechanism for operating elevator closures and more specifically is concerned with a mechanism for opening doors for freight elevator shafts.

A freight elevator is designed and intended for the handling of merchandise in large and heavy units, and may even be intended for carrying vehicles. Many freight elevators are therefore installed in shafts the landings of which have pairs of vertically sliding bi-parting doors, whereby a large opening can be completely uncovered because the doors move wholly within the shaft and need not be moved to one side thereof. Such doors are usually counterbalanced so that little power should be required to move the same. Nevertheless the size of such doors is such that it is essential that power be used to open and close the same. The problem has been heretofore solved by providing a motor or motors at each landing for operating each set of doors. Since the control of such motors must be in the car, obviously the electrical connections and circuits become complicated and expensive. Other constructions of the prior art have provided elongated members which extend the entire length of the shaft and have selective connection with the door opening mechanisms of the respective landings. Such constructions are cumbersome and limited as to shaft length. They are costly, and breakage and misadjustment all common faults.

I provide a motor upon the car, thereby eliminating all the motors at each floor, and a simple effective linkage mechanism at each floor designed to open the doors when the car is at that landing and the motor set in motion. Appropriate mechanical means providing a connection between the motor and the linkage is provided.

I realize that riding car door operators have been used in the prior art, but so far as I am aware, no previous construction has been made which provides a riding car operator working in connection with a simple linkage for opening vertically sliding counterbalanced doors; and it is the principal object of my invention to provide such a construction.

Other objects of the invention are: To provide a mechanism which is simple in design, thereby eliminating many expensive and complicated parts; to provide a mechanism which is simple to produce, operate, install, and repair, and one which can be used in altering present installations to achieve the results of my invention; to provide a mechanism in which there is no likelihood of jamming or binding of the doors.

2 Further objects of the invention lie in the provision of novel linkages at the landings; and specifically a novel linkage which when moved by the riding car operator will move the elevator hatchway doors perfectly vertically and wherein the point of engagement of the linkage with a door will remain on a vertical line as the door is being opened.

Many other objects of the invention will become apparent as the description proceeds.

Referring now to the drawings which illustrate a preferred embodiment of my invention, and in which:

Fig. 1 is an elevational view taken from the shaft side of a freight elevator installation having a mechanism constructed in accordance with my invention showing the doors leading to the landing closed and the car approaching the landing, with some of the details shown in section.

Fig. 2 is an elevational view taken from the landing side and showing the vertically sliding parting doors in closed condition.

Fig. 3 is a view similar to that of Fig. 1, but showing the car at the landing, with the doors still closed.

Fig. 4 is a detailed view of a modified form of the linkage of my invention which can be used with the installation shown in Fig. 1.

Fig. 5 is a view similar to that of Fig. 1 but showing the doors partially opened.

Fig. 6 is a view of the doors in the condition of Fig. 5 but taken from the landing side of the elevator installation.

Fig. 7 is a view similar to that of Fig. 5 but with the doors completely open.

Fig. 8 is a view of the open doors taken from the landing side.

Fig. 9 is a side elevational view of the linkage for opening the doors, with portions being shown in section to illustrate certain details, the doors being shown in closed condition.

Fig. 10 is a view similar to that of Fig. 9 but showing the doors partially open.

Fig. 11 is a view similar to that of Fig. 9 but showing the doors in completely opened condition.

Fig. 12 is a sectional view taken through the mechanism of Fig. 10 along the line 12—12 and in the indicated direction.

Fig. 13 is a sectional view taken along the line 13—13 of Fig. 10 and in the indicated direction.

Fig. 14 is a sectional view on a reduced scale taken through the cross-head of Fig. 12 and looking in the indicated direction.

Fig. 15 is a fragmentary side elevational view taken through the pitman or crank connection showing the limit switches.

Fig. 16 is a sectional view taken through the cross head along the line 16-16 of Fig. 14 and looking in the indicated direction.

Fig. 17 is a diagrammatic view of the electrical circuit of the mechanism.

Fig. 18 consists of four (4) kinematic diagrams showing various positions of the riding car operator linkage.

Referring now to the figures, the reference character 30 designates generally an elevator shaft which is built in a building and adapted to have an elevator car 31 move up or down therein. The car 31 is shown having a floor 32, side walls 33, and a roof 34. The construction of the elevator car 31 may be of any conventional type and any of the usual means for moving same up and down in the shaft may be used. For example, the car walls 33 are provided with guiding devices 36 adapted to engage and slide upon the elongated tracks 37 which are secured to the walls of the shaft 30 for its entire length. The car 31 may have a sheave 38 upon the roof 34 operating in connection with a cable 39 and a motor operated raising and lowering mechanism (not shown) in the penthouse of the elevator shaft 30 in any conventional manner. For convenience and clarity, none of the electrical control cables, chains, etc., that are usually associated with this type of installation are shown.

At each landing, there is provided a frame 40 defining an entrance way 41 into the shaft 30, but normally said entrance way 41 is covered by a pair of doors 42 and 43. Such doors are arranged to slide vertically, the upper door 42 moving upward and the lower door 43 moving downward, the doors being connected by means of cables 44 and 45 which pass over pulleys 46 and 47 respectively, secured to the wall of the shaft 30, so that not only will the doors move simultaneously, but their weights are counterbalanced one against the other so that only a relatively small amount of power is required to move the same. The ends of the cables 44 and 45 are secured to the doors by any convenient means such as for example eyes 50 and 51 secured to the respective doors as shown, and means (not shown in detail herein) may be provided for proper adjustment of the length of the respective cables 44 and 45 in any well-known manner.

The doors 42 and 43 are arranged to slide up and down and for this purpose may have extensions 53 and 54 along their edges arranged to slide in grooved members 55 secured to the frame 40 or the wall 130 of the shaft 30. The exact construction is unimportant to the novelty of this invention.

The elevator car 31 is intended to be moved to the landing with the car floor 32 at the floor level 56 of the landing at which time it is desired that the doors be opened. For this purpose, a riding car operator is provided. This operator consists of a mechanism which works in connection with a linkage provided at each landing, and uses only a single mechanical driving device which is carried by the car, thereby eliminating the need of having a motor and driving device at each of the landings.

On the roof 34 of the car there is provided a motor 60 which is controlled from the car 31, said motor being connected with a gear

reduction transmission 61 which has a crank wheel or disc 62 mounted for rotation with a stub shaft 63. The rotation of the motor in one direction or the other will rotate the stub shaft 63 in one direction or the other for the purpose of either opening or closing the doors 42 and 43. The wheel 62 has a crank arm 64 to which is pivoted the connecting rod 65 at 66. The connecting rod in turn is pivoted at 67 to a reciprocating plate 68 or similar member shown in Figs. 12 and 14. The plate or member 68 is adapted to reciprocate along the guide member 69, and for this purpose is secured to the cross-head 70 which has grooved members 71 and 72 in any desired manner engaging upon opposite edges of the guide member 69. The guide member 69 may be a simple metal strap supported at its center by spacers 73 and bolts 74 to an angle iron 75 which in turn is mounted upon the roof 34 of the car 31.

Obviously, rotation of the motor 60 will reciprocate the crosshead 70.

Considering for the moment the details of construction of the crosshead 70, note that same is formed as a vertically arranged channel-shaped member having a back portion 76 which is secured to the members 71 and 72 by fastening bolts and nuts 77 and 78 respectively, and having side portions 79 and 80 which serve as guide shoes to engage the actuating pin 81 of the door opening linkage. On the shoe 79 there is provided a switch actuating member 83 which is adapted to be depressed when the pin 81 enters the crosshead. This closes the switch 84 in the circuit of the motor 60 to enable the same to be operated. This will be explained in detail in connection with the description of the circuit of Fig. 17. Obviously the motor will not receive any power unless the pin 81 is disposed between the shoes 79 and 80.

The major parts of the operator have been explained and it will be seen that all of the mechanism for controlling the operator as well as the operator itself are carried by the car 31. I shall next describe the linkage which is connected with each of the sets of doors installed at the respective landings.

The basic type of linkage which embodies my invention is shown in Fig. 4 more or less diagrammatically. The pin 81' of this construction is identical with the pin 81 hereinabove discussed. The riding car operator is the same and hence the crosshead is designated generally 79. The pin 81' is carried on the end of arm 99 of the bell crank lever 91. The lever is pivoted at 92 to the wall 130 of the shaft 30 and the other arm 93 carries a sliding pin 94 engaged within and adapted to slide along the guides 95 secured to the door 42'. The counterbalancing mechanism is identical as that of the doors 42 and 43 but same is not shown in Fig. 4. As the crosshead 70 moves to the right, as viewed in Fig. 4, it rotates the bell crank 91 in a counter-clockwise direction about the pivot point 92. This moves the pin 94 in an arcuate path shown by the broken line 96 to the position shown at 94'. The broken line appearance of the bell crank at that point is designated 91', and that of the partially open door as 42'. The new position of the guides 95 is designated 95'. The movement of the bell crank 91' has now begun to open the door 42' and the vertical component of the motion of the pin 94 has been transmitted to the door 42' by upward pressure of said pin 94 against the upper guide member 95. There has been motion of the pin to the right of the center line 91 of the door 42 which

would tend to press the door against its frame if it weren't for the fact that the pin 94 is theoretically free to slide in the guides 95.

It will be seen that the construction of Fig. 4 is simple and effective to open vertically parting counterbalanced doors, and it should be obvious that an installation as described is easy to make and maintain.

Notwithstanding the efficacy of the construction described in connection with Fig. 4 it is desired to point out that there may be a tendency for binding in the doors especially since the upward force during opening of the doors is applied at a point which moves on both sides of the center of gravity of the upper door. Again, in lowering the door, the point of suspension moves on both sides of the center of gravity of the door. The novel linkage described hereinafter alleviates any possibility of such binding.

Referring now to Figs. 1, 3, 5, and 7 by way of preliminary discussion, I have referred to my novel bell crank lever by the general reference character 100. In Figs. 1 and 3, the bell crank lever 100 is slanted downwardly; in Fig. 5 it is disposed horizontally; and in Fig. 7 it is slanted upwardly. The pivot pin 101 by means of which the lever 100 is attached to the upper door 42, in each case may be positioned at the precise geometric center of the door and is pivotally mounted in an ear 102 rigidly affixed to the door 42 at the top thereof. The novelty of this phenomenon lies in the fact that although the body of the bell crank lever 100 is being pivotally rotated about a fixed point, the free end thereof is moving in a perfectly vertical straight line which may be on the center line 103 of the doors 42 and 43, eliminating binding, side-sway, and applying the lifting force upon that line during opening of the doors, or having the suspension point upon said line while the doors are being closed. This is shown in detail in Figs. 9, 10, and 11.

The lever 100 is a compound lever made up of three members, a casing 104, a sliding member 105, and a rocking member 106. The casing is L-shaped, having an elongate arm 107 provided with a channel 108 formed throughout the length thereof by means of narrow spacers 109 and 110 secured thereto. The spacer 109 extends along the entire length of the upper edge of the arm 107 but the spacer 110 terminates at the juncture of the short arm 111 with the arm 107 as indicated at 112. The arm 111 is wider than the arm 107 and is also provided with spacers 113 and 114 along its opposite edges, the spacer 114 joining spacer 110 at 112, while the spacer 113 terminates short of spacer 109 as shown at 115 for a purpose presently to be described.

The bottom edge of the arm 111 is not provided with a spacer, hence the casing is open at this point designated 116. The casing 104 is held in assembly with a cover member 117 having the identical shape as the casing. The cover member 117 is secured by means of bolts 118 which pass through the spacers as shown in the drawings and hold the entire casing in assembly. There are thus formed spaces within the arms of the casing for the accommodation of the sliding member 105 and the rocking member 106.

The sliding member 105 is an elongate metal strip designed to slide between the spacers 109 and 110 within the casing 104. At its right hand end as viewed in Fig. 9 it protrudes in and out of the casing as the lever 100 is being rotated in a manner to be described. The end 119 is provided with the pin 101, previously de-

scribed, and illustrated in Fig. 13. The pin 101 has a reduced diameter portion 121 pivotally secured to ear 102 and held in position by a pinned collar 122. Raising the lever end 119 obviously will raise the door 42.

At its opposite end 123 the sliding member 105 is provided upon its lower edge with a notch 124 which is rounded at the inner end thereof. The ball end 125 of the rocking member 106 10 is arranged in engagement with the notch 124 for the purpose of sliding the member 105 right or left. In certain positions, such as for example 15 that illustrated in Fig. 10 with the door either partially open, during opening the same or closing the same, the left end 123 of the sliding member 105 protrudes out of the casing 104 through the space 115 provided therefor between ends of the spacers 113 and 109.

To the rear of the casing 104 at the upper 20 end thereof there is rigidly secured a pin 126. This pin 126 has a shoulder forming thereby a reduced diameter portion 127 mounted in a bearing 128 secured to the wall 130 of the shaft 30 by means of bolts 131 and held against axial 25 motion by the pinned collar 132. The entire lever 100 is thus adapted to pivotally rotate about the pin 126.

Referring now to the member 106, it will be seen that same consists of a generally rectangular plate mounted to rock within the casing in the space formed at the arm 111. The upper narrowed end terminates in a ball 125 which is engaged within the notch 124 as previously explained. At its lower left hand end it is pivoted as shown at 133 to the casing 104 so that the rocking movement of the member 106 occurs about said point 133. The parts of member 106 thus far described are contained within the casing 104, but the lower right hand corner 134 of the member 106 protrudes from the casing through the space 116 and it will also be noted that the casing is foreshortened at this point as shown at 135 in Fig. 9 in order to permit the free movement of the corner 134.

45 The pin 81 is secured to the corner 134 and serves to engage the crosshead 70 of the riding car operator. Opposite to the pin 81 and on the right hand side of the casing 104 as viewed in Fig. 12 there is a pin 137 having a groove 138 and a head 139. An elongate plate 140 is secured to the wall 130 as shown in Fig. 16 by means of the bolts 41 the right hand portion of the plate extending beyond the frame 40 but being positioned in front of the door 43 as seen in Figs. 1, 3, 5, and 7. A pair of track members 142 are bolted to the plate by bolts 143 and have flanged edges 144 which engage within the groove 138 and thereby define a track for said groove 138. The defined track is designated by the character 145 in Figs. 9, 10, and 11. Inasmuch as the track 145 is horizontally disposed, the pin 137 must move on a horizontal line and cannot be withdrawn past the flanges 144 because of the head 139 being confined by said flanges.

70 The mechanism described caused the doors 42 and 43 to be opened or closed in a perfectly vertical movement because the rotation of the lever 100 will always result in a vertical movement of the pivot pin 101. This will be explained in detail hereafter.

75 Presume that the doors 43 and 42 are closed and the lever 100 is in the position shown in Figs. 9 and 1. When the elevator car 31 ap-

proaches and reaches the floor level 56 as shown in Fig. 3, the position of the lever 100 will not change, but remains as shown in Fig. 9, but now the pin 81 has been engaged by the cross-head 70 which has been brought up by the car, and the shoes 78 and 80 are disposed upon opposite sides of the pin 81. Now the operator is set into motion and the crosshead moves to the right as viewed in Fig. 10. Due to the confining action of the track 145, the pin 81 and its opposite mate 137 must move horizontally. This pulls the casing 104 of the lever 100 to the right because of the connection between the member 106 and the member 111 at 133, thus rotating the lever 100 about the pivot 126 in a counterclockwise direction as viewed in Fig. 10. Now as this occurs, the pivot 133 drops down relative to the line of the track 145, which is the path of movement of pin 81. This causes a rotative movement to be imparted to the plate member 132, which rocks in a counter-clockwise direction causing the ball 125 to execute an arcuate movement to the left about the pivot pin 133. This moves the member 105 to the left, retracting the portion 119 as the motion occurs, and eventually causing the end 123 to protrude from the casing 104 as shown in Fig. 10. During this time the pivot pin 101 moves upwardly in a perfectly vertical line along the center line 103. The movement of the ball 125 is arcuate, while the movement of the member 105 is rectilinear, and hence there will be relative movement between the ball 125 and notch 124 as evidenced by the partial withdrawal of the ball from the notch as shown in Fig. 10.

In Fig. 10, the lever 100 has moved while opening the doors to a point where the arm 107 is arranged on a substantially horizontal line. This phase of the movement has been illustrated because it shows the lever 100 in a condition where the sliding member 105 is at its extreme left. The doors 42 and 43 are partially separated and the riding car operator continues its movement, carrying the crosshead 70 further to the right.

This continues until the condition of Fig. 11 is reached in which the doors 42 and 43 are fully opened and the riding car operator has stopped moving the crosshead 70. I shall now describe the movements of the various parts which result in the condition shown in Fig. 11 from that shown in Fig. 10. As the crosshead 70 moves to the right in Fig. 10, the pivot pin 133 drops below the line of the track 145. The lever 100 is still being pivoted in a counterclockwise direction about the pin 126, but the moment that the vertical axis of the pin 81 passes the vertical axis of the pin 126, the relative rotation of the rocking member 106 caused by the movement of the pin 133 downwardly is clockwise. That is, the motion is clockwise relative to the casing 104. The ball 125 is still being slightly withdrawn from the notch 124, but the motion of the sliding member 105 is reversed, and hence it moves to the right, with the end 119 gradually protruding more and more from the end of the casing 104. The net effect is that the door 42 is raised in a perfectly vertical motion, there being no side-sway or binding whatever, and less force need be applied by the riding car operator.

The remainder of this description is more or less of a general nature since many different types of control circuits can be used, and many different types of control mechanisms can be used with my invention.

Attention is invited to Figs. 15 and 17 in which 76 has its contacts 202 engaged by the circuit break-

are respectively shown the pitman connection to the connecting rod 65 and the electrical control circuit for opening and closing the doors 42 and 43. The circuit and controls for moving the elevator car 31 up and down are not shown in order to keep the explanation as simple and clear as possible. The kinematic diagrams of the riding car operator are shown in Fig. 18.

The limit switches for controlling the extent of movement of the crosshead are shown in Fig. 15 and designated 200 and 201. Each operates in connection with a pair of contacts 202 and 203 which ride upon the disc 62 so that normally the switches are closed, permitting the motor 60 to drive the disc and the connecting rod 65. Normally, with doors closed and the control circuit quiescent, the connecting rod is arranged as shown kinematically in Fig. 18 at A. The pin 81 is in the precise center between the shoes of the crosshead 70, and the pin 66 is below the horizontal axis of the disc 62. Under these circumstances, the limit switch 201 has its contacts 203 engaged by the circuit breaking pin 204 which is installed at an appropriate place upon disc 62 and the motor cannot be set in operation through the lead 205 controlled by said switch. Presume that the switch 84 is closed. The elevator attendant closes switch 203 in lead 207 (which may be done for example, by shutting off the up and down controls in any well-known manner not illustrated or described herein) and now the line is connected through leads 207 and 208 to the primary 209 of the transformer 210. The lead 208 is a common lead for the motor 60 and the transformer 210. The secondary 211 is a low voltage winding, and is now open. If the attendant presses a button or the like for closing the "close" switch 212 nothing will happen because the switch 201 in the lead 205 is open. If the attendant presses the "open" switch 213, the circuit comprising secondary 211, lead 214, coil 215, switch 200, windings of motor 60, and lead 208 will be closed. The motor 60 will therefore start to rotate driving the disc 62 in a clockwise direction as viewed in A of Fig. 18. Simultaneously, the coil 215 will draw the solenoid core 217 upwards so that bar 218 engages contacts 219 and 220 closing the circuit of lead 221 which by-passes the transformer 210. The bar 218 is held in this condition, keeping the motor circuit 216 closed without the additional load of transformer 210. Those skilled in the art will recognize the above as the description of the operation of a holding switch, so that in the event the switch 213 is constructed as a momentary contact button, it need only be depressed a short time to set the riding car operator into operation.

Returning now to Fig. 18, the disc 62 is now rotating in a clockwise direction. In A the pin 81 was in the center of the crosshead 70 so that in the vertical movement of the car 31, the pins of the respective floors would offer no interference to passage of said crosshead 70. Now, as the disc rotates carrying the connecting rod 65 to position shown in A, the crosshead 70 moves to the left, and nothing additional occurs. Between B and C, the crosshead 70 is taking up the slack and the shoe 80 has finally engaged the pin 81 and is now beginning to rotate the lever 100. As the pin 66 is carried over the top of its travel, the doors are opened, until, the connecting rod 65 is arranged as shown in D of Fig. 18, horizontally, with pin 81 still engaged against the shoe 80. At this point, the limit switch 200 has its contacts 202 engaged by the circuit break-

ing pin 222 which opens the lead 216 and stops the rotation of the motor 60. In the meantime, the circuit breaking pin 204 has left the contacts 203 permitting the switch 201 to close.

Presume now that the passengers or freight have been discharged from the car 31, the operator presses the button closing switch 212. This closes the circuit of lead 223 connected with secondary 211 to coil 224 and through lead 205 through switch 231 and back to the line through motor 60 and lead 208. This causes the motor to begin to rotate in a direction opposite to that which it rotates when lead 216 is connected thereto. The flow of current through the coil 224 pulls the core 217 downwardly, causing the bar 218 to leave contacts 219 and 220 and engage contacts 225 and 226, short circuiting the transformer 210 and holding the circuit to lead 221 and lead 207 closed.

The disc of Fig. 18, part D now commences to rotate in a counterclockwise direction. Nothing occurs at first while the shoe 79 takes up slack between it and pin 81 as the pin 66 rides up around the disc 62. Finally shoe 79 engages pin 81 as shown by the broken lines of Fig. 18 part A. Thereafter, continued rotation of the disc closes the doors leaving the pin 81 and the crosshead 70 exactly as shown in Fig. 18 part B. The discs 62, however, continues to rotate and this brings the crosshead 70 back to the position shown in Fig. 18 part A, at which time the limit switch 201 is opened as described.

Many safety and mechanical features not shown or described in this specification can be used with my invention. Latches, interlocks, and similar devices are relatively easy to associate with my construction because of the simplicity thereof. It is also practical to connect a car door with the operating mechanism such as by having the riding car operator open the same simultaneously with the landing doors, but this forms no part of my invention.

It is believed that my invention, its mode of construction and assembly, and many of its advantages should be readily understood from the foregoing without further description, and it should be manifest that while a preferred embodiment of the invention has been shown and described for illustrative purposes, the structural details are nevertheless capable of wide variation within the purview of this invention as defined in the appended claims.

What is claimed and desired to be secured by Letters Patent of the United States is:

1. An elevator installation comprising a shaft having a plurality of landings and a car traveling up and down in the shaft and adapted to stop at the landings as desired, each of said landings having a pair of bi-parting vertically slideable counterbalanced doors, one of which is adapted to slide upward and the other of which is adapted to slide downward, a mechanical linkage attached to the wall of the shaft at each landing, each of said linkages being connected with the pair of doors at the respective landings and each including a pin poised adjacent the path of travel of said car, a riding car operator upon the car having a horizontally movable crosshead adapted to be reciprocated for opening and closing the landing doors, the crosshead adapted to move vertically with the car as same travels in the shaft and adapted to be arranged in coupling engagement with the pin of any landing when the car is at said landing, and means for moving the crosshead horizontally

when at said landing whereby said pin will be moved operating said linkage to open the doors with movement of the crosshead in one direction, and said pin will be moved to close the doors when the crosshead is moved in a reverse direction.

2. An elevator installation comprising a shaft having a plurality of landings and a car traveling up and down in the shaft and adapted to stop at the landings as desired, each of said landings having a pair of bi-parting vertically slideable counterbalanced doors, one of which is adapted to slide upward and the other of which is adapted to slide downward, a mechanical linkage attached to the wall of the shaft at each landing, each of said linkages being connected with the pair of doors at the respective landings and each including a pin poised adjacent the path of travel of said car, a riding car operator upon the car having a horizontally movable crosshead adapted to be reciprocated for opening and closing the landing doors, the crosshead adapted to move vertically with the car as same travels in the shaft and adapted to be arranged in coupling engagement with the pin of any landing when the car is at said landing, and means for moving the crosshead horizontally when at said landing whereby said pin will be moved operating said linkage to open the doors with movement of the crosshead in one direction, and said pin will be moved to close the doors when the crosshead is moved in a reverse direction, said linkage comprising a bell crank lever having two arms pivoted to said shaft and having said pin secured to one arm and the other arm connected with the upward sliding doors substantially at the center thereof and above the center of gravity.

3. An elevator installation comprising a shaft having a plurality of landings and a car traveling up and down in the shaft and adapted to stop at the landings as desired, each of said landings having a pair of bi-parting vertically slideable counterbalanced doors, one of which is adapted to slide upward and the other of which is adapted to slide downward, a mechanical linkage attached to the wall of the shaft at each landing, each of said linkages being connected with the pair of doors at the respective landings and each including a pin poised adjacent the path of travel of said car, a riding car operator upon the car having a horizontally movable crosshead adapted to be reciprocated for opening and closing the landing doors, the crosshead adapted to move vertically with the car as same travels in the shaft and adapted to be arranged in coupling engagement with the pin of any landing when the car is at said landing, and means for moving the crosshead horizontally when at said landing whereby said pin will be moved operating said linkage to open the doors with movement of the crosshead in one direction, and said pin will be moved to close the doors when the crosshead is moved in a reverse direction, said linkage comprising a bell crank lever having two arms pivoted to said shaft and having said pin secured to one arm and the other arm connected with the upward sliding doors substantially at the center thereof and above the center of gravity.

4. A mechanism for opening a pair of bi-parting vertically sliding counterbalanced doors from a car approaching and stopping at said doors, said doors being mounted for uncovering and covering an opening at a landing of an elevator shaft and said car riding up and down in the shaft and having a riding car operator thereon, and providing a horizontally movable actuating member, comprising a bell crank lever pivotally

mounted in the shaft on the wall and to one side of the opening and having two arms, one arm being pivotally secured to one of said doors at a point adjacent the center thereof, the second arm adapted to be coupled to said actuating member of the riding car operator when the car is opposite the opening, said lever adapted to be rotated about its pivot point when the actuating member is moved to move the doors vertically, the first mentioned arm being movable relative to the pivot point of the lever to change the effective length of said arm, and means maintaining the said point of pivotal securement of said first arm to the door in a substantially vertical line as the doors are moved vertically.

5. A mechanism for opening a pair of bi-parting vertically sliding counterbalanced doors from a car approaching and stopping at said doors, said doors being mounted for uncovering and covering an opening at a landing of an elevator shaft and said car riding up and down in the shaft and having a riding car operator thereon, and providing a horizontally movable actuating member, comprising a compound bell crank lever pivotally mounted in the shaft on a wall thereof and having one arm provided with a telescoping member, and a second arm provided with a rocking member, the rocking and telescoping members being articulatedly attached, the telescoping member being pivotally secured to one of said doors, and the rocking member being adapted to be coupled with said actuating member, and means causing the telescoping member to slide relative to said first mentioned arm varying the distance from the door pivot point to the wall pivot point as the rocking member is horizontally moved and said compound lever rotated.

6. A mechanism for opening a pair of bi-parting vertically sliding counterbalanced doors from a car approaching and stopping at said doors, said doors being mounted for uncovering and covering an opening at a landing of an elevator shaft and said car riding up and down in the shaft and having a riding car operator thereon, and providing a horizontally movable actuating member, comprising a compound bell crank lever pivotally mounted in the shaft on a wall thereof and having one arm provided with a telescoping member, and a second arm provided with a rocking member, the rocking and telescoping members being articulatedly attached, the telescoping member being pivotally secured to one of said doors, and the rocking member being adapted to be coupled with said actuating member, and means causing the telescoping member to slide relative to said first mentioned arm varying the distance from the door pivot point to the wall pivot point as the rocking member is horizontally moved and said compound lever rotated, said means being arranged to cause movement of the door pivot point in other than an arc about the wall pivot point.

7. A mechanism for opening a pair of bi-parting vertically sliding counterbalanced doors from a car approaching and stopping at said doors, said doors being mounted for uncovering and covering an opening at a landing of an elevator shaft and said car riding up and down in the shaft and having a riding car operator thereon, and providing a horizontally movable actuating member, comprising a compound bell crank lever pivotally mounted in the shaft on a wall thereof and having one arm provided with a telescoping member, and a second arm provided with a rocking member, the rocking and telescoping

members being articulatedly attached, the telescoping member being pivotally secured to one of said doors, and the rocking member being adapted to be coupled with said actuating member, and means causing the telescoping member to slide relative to said first mentioned arm varying the distance from the door pivot point to the wall pivot point as the rocking member is horizontally moved and said compound lever rotated, said means being arranged to cause movement of the door pivot point in a substantially vertical straight line during rotation of the compound lever.

8. A mechanism for opening a pair of bi-parting vertically sliding counterbalanced doors from a car approaching and stopping at said doors, said doors being mounted for uncovering and covering an opening at a landing of an elevator shaft and said car riding up and down in the shaft and having a riding car operator thereon, and providing a horizontally movable actuating member, comprising a compound bell crank lever pivotally mounted in the shaft on a wall thereof and having one arm provided with a telescoping member, and a second arm provided with a rocking member, the rocking and telescoping members being articulatedly attached, the telescoping member being pivotally secured to one of said doors, and the rocking member being adapted to be coupled with said actuating member, and means causing the telescoping member to slide relative to said first mentioned arm varying the distance from the door pivot point to the wall pivot point as the rocking member is horizontally moved and said compound lever rotated, said rocking member having a pin providing said coupling, said means comprising a track confining movement of said pin to horizontal, a pivotal connection between said rocking member and said second arm adjacent the end of the second arm, and said articulated connection including a ball and recess joint permitting movement of the rocking member relative to the sliding member as the former slides the latter.

9. In a device of the character described, a pivotally mounted compound bell crank lever having two arms one of which is adapted to be secured to a first point on a vertically moving door, and the second of which is adapted to have a second point thereof moved horizontally to rotate the lever and move the door, means causing the said first point to move in a vertical straight line as second arm is moved horizontally, and comprising said lever being formed of three parts, a casing having two branches pivotally mounted at the juncture thereof, a slidable member movable parallel to the first branch, and a rocking member movable relative to the second branch, the said first arm being formed of the first branch and the slidable member, and the said second arm being formed of said second branch and the rocking member, said rocking and sliding members being articulatedly connected whereby as said lever rotates, the slidable member will slide relative to the said first branch.

10. In a device of the character described, a pivotally mounted compound bell crank lever having two arms one of which is adapted to be secured to a first point on a vertically moving door, and the second of which is adapted to have a second point thereof moved horizontally to rotate the lever and move the door, means causing the said first point to move in a vertical straight line as second arm is moved horizontally, and comprising said lever being formed of three parts,

a casing having two branches pivotally mounted at the juncture thereof, a slidable member movable parallel to the first branch, and a rocking member movable relative to the second branch, the said first arm being formed of the first branch and the slidable member, and the said second arm being formed of said second branch and the rocking member, said rocking and sliding members being articulatedly connected whereby as said lever rotates, the slidable member will slide relative to the said first branch, the rocking member being pivotally connected with the second branch whereby to rock relative thereto, and the articulated connection including means to permit relative and hinged movement between rocking and sliding members at the same time.

11. In a device of the character described, a pivotally mounted compound bell crank lever having two arms one of which is adapted to be secured to a first point on a vertically moving door, and the second of which is adapted to have a second point thereof moved horizontally to rotate the lever and move the door, means causing the said first point to move in a vertical straight line as second arm is moved horizontally, and comprising said lever being formed of three parts, a casing having two branches pivotally mounted at the juncture thereof, a slidable member movable parallel to the first branch, and a rocking member movable relative to the second branch, the said first arm being formed of the first branch and the slidable member, and the said second arm being formed of said second branch and the rocking member, said rocking and sliding members being articulatedly connected whereby as said lever rotates, the slidable member will slide relative to the said first branch, the rocking member being pivotally connected with the second branch whereby to rock relative thereto, and the articulated connection including means to permit relative and hinged movement between rocking and sliding members at the same time, comprising a ball and recess joint, the recess having parallel sides permitting partial withdrawal of the ball.

12. In a device of the character described, for opening the doors of an elevator installation including a fixed wall, a substantially L-shaped casing forming a long and a short branch, the casing being pivotally mounted on said wall for rotation, a member slidably telescoped in the long branch and having its outer end secured to a point on a door, a rocking member disposed in the short branch and having a pivotal connection with said casing adjacent the end of the short branch, an end of the rocking member protruding from the casing and having a coupling device thereon, means secured to said wall confining movement of said coupling device to horizontal, and said rocking member having articulated connection with said sliding member within said casing whereby horizontal movement of said coupling device will cause rocking of the rocking member, rotation of the casing, and sliding movement of the sliding member, whereby the said outer end will raise the door with rectilinear movement of said point.

13. In a device of the character described, for opening the doors of an elevator installation including a fixed wall, a substantially L-shaped casing forming a long and a short branch, the casing being pivotally mounted on said wall for rotation, a member slidably telescoped in the long branch and having its outer end secured to a point on a door, a rocking member disposed

in the short branch and having a pivotal connection with said casing adjacent the end of the short branch, an end of the rocking member protruding from the casing and having a coupling device thereon, means secured to said wall confining movement of said coupling device to horizontal, and said rocking member having articulated connection with said sliding member within said casing whereby horizontal movement of said coupling device will cause rocking of the rocking member, rotation of the casing, and sliding movement of the sliding member, whereby the said outer end will raise the door with rectilinear movement of said point, said articulated connection comprising a ball formation on said rocking member and a parallel sided recess formed upon an edge of said sliding member whereby said rocking member may move perpendicularly relative to the sliding member while causing sliding movement thereof.

14. In combination with an elevator installation having a shaft, a shaft wall, a car moving up and down in said shaft, a landing opening, and vertically slidably bi-parting counterbalanced doors, means for opening the doors, comprising a riding car operator having a horizontally movable vertically disposed channel-shaped cross head with juxtaposed shoes, a source of rotating motive power upon the car, a crank adapted to be rotated by the motive power, a connecting rod between the crank and crosshead for moving the crosshead horizontally, a compound bell crank lever pivotally mounted adjacent the landing opening upon the wall, a pin secured to the lever and poised in the path of the crosshead as the car moves up and down whereby when the car is adjacent the landing opening the pin will be arranged between the shoes, the lever being connected with the doors and adapted to open the same when the lever is rotated, and said crosshead adapted to be moved horizontally when the car is at the landing opening to cause rotation of the lever.

15. In a combination with an elevator installation having a shaft, a shaft wall, a car moving up and down in said shaft, a landing opening, and vertically slidably bi-parting counterbalanced doors, means for opening the doors, comprising a riding car operator having a horizontally movable vertically disposed channel-shaped cross head with juxtaposed shoes, a source of rotating motive power upon the car, a crank adapted to be rotated by the motive power, a connecting rod between the crank and crosshead for moving the crosshead horizontally, a compound bell crank lever pivotally mounted adjacent the landing opening upon the wall, a pin secured to the lever and poised in the path of the crosshead as the car moves up and down whereby when the car is adjacent the landing opening the pin will be arranged between the shoes, the lever being connected with the doors and adapted to open the same when the lever is rotated, and said crosshead adapted to be moved horizontally when the car is at the landing opening to cause rotation of the lever, and means associated with the crosshead for preventing operation of the motive power unless the said pin is poised between the shoes.

16. In a device of the character described for opening a slidable door movable relative to a fixed door frame, a pivotally mounted bell crank lever having its pivot fixed relative to said frame, said lever having two arms one of said arms having pivot means in the end thereof adapted

15

pivoted to be attached to a point on said door and the second arm adapted to be driven in a direction so as to rotate the lever and said first arm, and kinematic means movable relative to said lever mounted on said lever and actuated by the rotation thereof and serving to vary the effective length of said first lever arm during rotation whereby said pivot means will move in a predetermined non-circular path.

17. In a device of the character described for opening a slidable door moving relative to a fixed door frame, means serving to apply force to said door along a line substantially parallel with the direction of movement of said door, and comprising a pivotally mounted compound bell 15 crank lever having two arms one of which is

16

adapted to be pivoted to the door, the center of the crank lever adapted to be pivotally mounted with its pivot point fixed relative to said frame, the second arm adapted to be moved in a direction substantially perpendicular to the direction of movement of the door to rotate the lever, said first lever arm having a portion slidable lengthwise thereof to vary the effective length thereof, a pivot on said portion providing for said pivotal attachment to said door, and a linkage associated with the second lever arm and connected with said slidable portion to slide the same during rotation of the lever.
